UNITED STATES PATENT OFFICE.

THOMAS SLOPER, OF WILTS, AND ISAAC HARDY PARSONS, OF LEICESTER,
ENGLAND.

INTERCOMMUNICATION TELEPHONE SYSTEM.

SPECIFICATION forming part of Letters Patent No. 718,224, dated January 13, 1903.

Application filed April 18, 1902. Serial No. 103,652. (No model.)

To all whom it may concern:

Be it known that we, THOMAS SLOPER, of 14 Brittox, Devizes, Wilts, and ISAAC HARDY PARSONS, of Faraday Works, Leicester, England, subjects of the King of Great Britain, have invented new and useful Improvements 5 in Intercommunication Telephone Systems, of which the following is a specification.

This invention relates to improvements in 10 intercommunication telephone systems of the kind wherein each instrument is provided with a pair of home lines having extensions or forks whereby the said lines can be connected to jacks or connecting devices at other 15 instruments of the system. In such systems as heretofore constructed it is possible for a person to tap or overhear a conversation being carried on between two subscribers by simply connecting his switch to one of the 20 speaking-lines, and it is even found in practice that overhearing can take place if only one terminal of the receiver at the tapping-station is connected to any part of a speaking-line.

25 Now this invention has for its object to obviate this defect, and to this end instead of connecting both the transmitter and the receiver of each instrument to the same lines or the same induction-coil, as has heretofore 30 been the practice, we arrange the connections in such a manner that the receiver at each instrument is always disconnected from the transmitting apparatus of the same instrument and also from the switch or other device 35 made use of for connection with the lines of the other stations of the system, and from the "earth" or common return-wire, (if any.) By "transmitting" apparatus we mean the microphone induction-coil or other apparatus 40 for producing the necessary current or variation of potential either directly or by induction. With this arrangement it will be understood that the operator at each instrument cannot connect his receiver to any other line 45 than his own, so that although he can hear what is spoken into his own pair of lines from any of the stations yet he can only speak to the station to the lines of which he is connected by his plug or switch.

50 In the accompanying drawings, Figure 1 is a diagrammatic view representing two tele-

phone-stations connected up according to the invention. Fig. 2 is a similar view illustrating a slight modification.

The same characters of reference refer to 55 the same or corresponding parts in both figures.

A and B represent the two stations.

a a are the receivers; b b, the receiver-hooks; c c, the transmitters; d d, the bells; 60 e e, the switches or plugs which are adapted to be connected to the jacks f f for connecting up the two stations, as hereinafter described.

g is the battery in the transmitter-circuit, 65 and 1, 2, 3, 4, 5, and 6 represent the home lines with which receivers of the different stations are connected, the jacks f f being also connected to these lines, as clearly shown. With this arrangement when an operator 70 at, say, station A desires to call up an operator at station B he brings his plug e in connection with the jacks f f, attached to the lines 1 and 2, and depresses the key or contact g', whereupon the current flows 75 through the wire 7, contact g', wire 8, plug e, jack f, home line 2, wire 9 at station B, bell d, receiver-hook b, wire 10, home line 1, jack f at station A, plug e, and wire 11 back to the battery. The bell at station B is therefore 80 rung, announcing to the operator in this station that some one wishes to speak to him. He must therefore remove his receiver from its hook, thereby placing it in circuit with the transmitter at the calling-station A, the 85 operator at which station can then announce to him his number. Upon receiving the number the operator at station B places his plug e into connection with the home lines corresponding to station A, whereupon his transmitter is brought into electrical connection with the receiver at station A, thus enabling the operator at the second station to converse. It will thus be seen that the receiver at each station is in connection only with the 95 transmitter at the other station—that is to say, with the station to which it is connected by means of the plug or switch—so that it is impossible for an operator at a third station to overhear the conversation which is proceeding, as his home line cannot be brought 100 into electrical connection with the transmit-

ter at either of the stations between which conversation is proceeding.

5 *h* is a buzzer or other suitable sounding device which is used for indicating to the operator at the calling-station that his call is answered, and in the arrangement shown in Fig. 1 this buzzer is inserted in the signaling-circuit, being advantageously operated by the signaling-current, although an independent 10 signaling-current at the called station may be used, if found more convenient.

In order that the signaling-current at a third station shall not be sent through a receiver at either one of the two stations in conversation, 15 we may connect one terminal of the bell at each station to a common return-line *i* or earth, as is indicated in the arrangement shown in Fig. 2. In this arrangement we have shown a magneto-machine *j* for generating 20 the necessary current for signaling purposes, although we wish it to be understood that an ordinary ringing-battery could be employed, if desired, and also that such a magneto-generator could be used for ringing in the arrangement shown in Fig. 1 in lieu of the battery there illustrated.

When the connections are made as shown in Fig. 2 and the subscriber at station A desires to ring up the subscriber at station B, 30 the subscriber at the former station operates his magneto-generator *j* so as to cause a current to flow from the said generator through the line 11, switch-plug *e*, jack *f*, home line 1, line 10 at station B, receiver-hook *b*, bell *d*, 35 and common return-line or earth *i* back to the generator *j*. A key may be provided at *k*, which may be operated by hand while ringing, or it may be so arranged that it is automatically operated when the generator is 40 used.

Assume now that the receiver at station B is removed from its hook and that a subscriber at another station endeavors to ring up station B. In this case the circuit between the home line 1 and the return-wire *i* 45 is broken at the receiver-hook *b*, so that no current flows, and thus the subscriber using the receiver at station B is not subjected to the annoyance of being rung up while he is 50 using the receiver. At the same time the subscriber at the calling-station is made aware that the subscriber at station B is engaged, as he receives no announcement on his sounder that his signal has been received.

55 Having now particularly described and ascertained the nature of our said invention and in what manner the same is to be performed, we declare that what we claim is—

1. In an intercommunication telephone system, the combination of a plurality of stations 60 each having a receiver, a circuit for the receiver extending to the other stations, and a transmitter at all times entirely disconnected from the said receiver-circuit, and adapted 65 to be connected to the receiver-circuit of another station, substantially as described.

2. In an intercommunication telephone sys-

tem, the combination of a plurality of stations each provided with a transmitter and a receiver at all times in a different circuit from 70 the transmitter, and means for connecting the transmitter of one station with the receiver only of other stations, substantially as described.

3. In an intercommunication telephone sys- 75 tem, the combination of a plurality of stations each provided with a transmitter and a receiver in a different circuit from the transmitter, a plurality of lines connecting said stations, and a circuit-controlling device for 80 each station, in the transmitter-circuit thereof for connecting said transmitter with the receiver of a called station, substantially as described.

4. In an intercommunication telephone sys- 85 tem, the combination of a plurality of stations, each station having its receiver and transmitter in separate and independent circuits and a circuit-controller in a circuit independent of the receiver-circuit for connecting the 90 transmitter of one station to the receiver of other stations, substantially as described.

5. In an intercommunication telephone sys- tem, the combination of a plurality of stations, each having a receiver and a transmitter and 95 a pair of home-line wires connected to its receiver only, and extending to each of the other stations and means at each station for placing the transmitter only thereof in connection with the home lines leading to the receiver 100 only of another station, substantially as described.

6. In an intercommunication telephone sys- tem, the combination of a plurality of stations each having a receiver, a pair of home lines 105 for the receiver leading to each of the other stations, a call device in a shunt-circuit connected with said home lines, a transmitter, at all times disconnected from said home lines leading to the receiver, a circuit-controller 110 for connecting said transmitter with the home lines, of another station, and a switch for cutting the said call device out of the receiver-circuit and placing the receiver in said circuit, substantially as described.

7. In an intercommunication telephone sys- tem, the combination of a plurality of stations each having a receiver, a pair of home lines therefor, leading to all the other stations, a call device in a shunt of the receiver-circuit, a switch for cutting out said call device and placing said receiver in connection with said home lines, a transmitter at all times disconnected from said home lines, a separate circuit for said transmitter, a controller in said circuit for placing the transmitter in connection with the home lines leading to the receiver of another circuit and an electric signal in said transmitter-circuit, substantially as described.

8. In an intercommunication telephone sys- tem, the combination of a plurality of stations each having a receiver, a pair of home lines therefor, leading to all the other sta-

tions, a call device in a shunt of the receiver-circuit, a switch for cutting out said call device and placing said receiver in connection with said home lines, a transmitter at all 5 times disconnected from said home lines, a separate circuit for said transmitter, a controller in said circuit for placing the transmitter in connection with the home lines leading to the receiver of another circuit, an 10 electric signal in a shunt-circuit in said transmitter-circuit and a switch for cutting said signal into and out of said circuit, substantially as described.

9. In an intercommunication telephone system, the combination of a plurality of stations each provided with a receiver, a circuit therefor including a pair of home lines leading to all the other stations, a call device in 15 a shunt-circuit of said receiver-circuit, a

transmitter, a normally open circuit therefor 20 at all times disconnected from said receiver-circuit, a controller in the transmitter-circuit for connecting it with the home lines leading to a receiver of another station, a call-switch making and breaking a shunt-circuit connected with said transmitter-circuit, an electric return-call signal in said shunt-circuit, and a switch for cutting out the call device in the receiver-circuit and cutting in the receiver and simultaneously closing the independent transmitter-circuit, substantially as 25 30 described.
